UNITED STATES PATENT OFFICE.

ALEXANDER T. McMURTRY, OF MEDFORD, OREGON.

QUARTZ-MILL.

SPECIFICATION forming part of Letters Patent No. 655,793, dated August 14, 1900.

Application filed September 2, 1899. Serial No. 729,356. (No model.)

To all whom it may concern:

Be it known that I, ALEXANDER T. McMURTRY, residing at Medford, in the county of Jackson and State of Oregon, have invented 5 a new and useful Quartz-Mill, of which the following is a specification.

My invention relates to quartz-mills, and particularly to an improved quartz-mill employing loose rollers or shoes, and has for its 10 object the general improvement of the construction and operation of such mills.

With this object in view my invention consists in the improved construction, arrangement, and combination of parts hereinafter 15 fully described and afterward specifically pointed out in the appended claims.

In order to enable others skilled in the art to which my invention most nearly appertains to make and use the same, I will now proceed 20 to describe its construction and operation, reference being had to the accompanying drawings, forming part hereof, in which—

Figure 1 is a vertical sectional view of a mill constructed in accordance with my invention, part of the feeding mechanism being 25 shown. Fig. 2 is a horizontal sectional view on the plane indicated by the dotted line *a b* of Fig. 1 looking downward. Fig. 3 is a horizontal sectional view on the plane indicated 30 by the dotted line *c d* of Fig. 1. Fig. 4 is a detail perspective view of the inner and outer cylinder and clutch detached. Fig. 5 is a top plan view of the four-armed yoke or spider. Fig. 6 is a view in side elevation of the feeder-cam. Fig. 7 is a top plan view of the muller-cap or toothed driving-cam. Fig. 8 is a detail perspective view of one of the knees for 35 supporting the muller-cap. Fig. 9 is a similar view of one of the mullers detached. Fig.

40 Fig. 10 is a similar view illustrating a hollow or shell shoe or roller and a solid one. Fig. 11 is a similar view illustrating two forms of muller-connecting bars or bolts. Fig. 12 is a plan view of the dies. Fig. 13 is a detail perspective view of the coupling-pin. Fig. 14 is a detail perspective view of the false rim sometimes used when the screen is omitted. 45

Like numerals of reference mark the same parts wherever they occur in the several figures of the drawings.

Referring to the drawings by numerals, 1

indicates a step-bearing secured to any suitable base, in which is journaled a vertical shaft 2, upon which is keyed or otherwise secured a bevel gear-wheel 3, engaging the lower 55 edge of a bevel gear-wheel 4 on horizontal shaft 5, which is driven from any suitable power and is the driving-shaft of the machine, thereby driving the vertical shaft 2 in one direction. Above the wheel 3 on shaft 2 is a 60 collar 6, adjustably fixed by means of a set-screw 7. This collar supports a bevel gear-wheel 8, loosely mounted on the shaft 2 and engaging the upper edge of gear-wheel 5, thereby driving the gear-wheel 8 in a direction opposite to the direction of the shaft 2 and gear-wheel 3.

Near the upper end of shaft 2 is a collar 9, adjustably but firmly secured to the shaft by means of set-screws 10. Upon this collar 9 70 rests a four-armed yoke 11, keyed upon shaft 2 to rotate therewith, each of the arms of the yoke being slotted, as at 12, to receive bolts 13, which secure knees 14 to the arms. These knees are constructed as shown in detail in 75 Fig. 8, being provided with upper horizontal ends 15 to receive the bolts 13 and lower outwardly - projected ends 16 to receive the muller-cap or driving-ring 17, being secured thereto by bolts 18, which also secure a dished 80 ring 19 to the cap, forming a hopper-mouth to receive and conduct the material from spout 20 of tank or box 21. A cam 22 is secured to each arm of the yoke and serves to intermittently raise and drop the spout through the 85 medium of a bar 23, secured thereto and lying in the path of rotation of the cams. The cams are secured by bolts 24, passing through the yoke-arms.

25 indicates the pan of the mill, mounted 90 rigidly and provided with a vertical rim 26 at its outer edge and a similar central rim forming what I denominate the "intermediate cylinder" 27. In the pan are loosely set the outer cylinder 28, the shoes or rollers 29, and the 95 mullers 30, the cylinder 28 resting upon sectional circular dies 31, the shoes on similar dies 32, and the mullers on similar dies 33. The cylinder 28 is provided with diametrically opposite notches 34 in its upper edges, in 100 which rest the wings or lugs 35 of a ring-clutch 36, provided with diametrically-oppo-

site notches 37 in its inner face intermediate of and ninety degrees removed from the lugs to receive outwardly-projecting wings or lugs 38 on the upper end of an inner cylinder 39, surrounding shaft 2 and secured in an annular groove in the upper face of bevel gear-wheel 8. The shoes surround the other cylinder 28, are set loosely on end, and are hollow or solid short cylindrical structures, when hollow being tightly plugged with hard wood, as at 40. The mullers are of substantially-segmental shape, being sections of a flat ring with inner and end vertical flanges, as at 41 42, the end flanges being notched in their upper edges, 15 as at 43, to receive the headed bolts 44 for connecting the mullers. These bolts are provided with nuts 45 for adjustment, or they may be solid-headed bars, as at 46 in Fig. 11. One of these connecting-bolts, as at 47, is provided with a central eye 48 to receive a coupling-pin 49, which passes downward through the muller-cap or driving-ring 17, tension-plates 50 being placed under the head of the pin and secured to the cap by a screw. 20

25 By means of their connections with the gear-wheel 8 and with each other the inner and outer cylinders 39 and 38 are driven in the opposite direction to the rotation of the shaft 2, and by means of the yoke, knees, cap, and coupling-pin the mullers are driven in the opposite direction to the cylinders or in the same direction as the shaft. By this means the quartz is thrown in both directions against and between the shoes and is thus 30 thoroughly and quickly ground up or pulverized. The rotation of the mill throws the water outward through a screen secured to the pan into a surrounding trough 51, and the pan may be entirely emptied by removing the screw-plug 52. Wearing-shoes may be attached to each muller, if desired, the shoes may be made of any suitable size, the slots to receive the muller-connecting bolts may be vertical, horizontal, or diagonal, and the 35 screen may be dispensed with, a false rim 53 being then used. The outer cylinder may be made non-rotatable and may, if desired, be made in sections secured together by lugs and steel band. 40

45 The pan may be used as an amalgamating-pan to work sulfurets or tailings. As the outer cylinder wears off at the bottom a bracket may be put into the slots in its upper edge, as shown in dotted lines in Fig. 4, to raise the clutch-ring lugs to proper height. 50

Having thus fully described my invention, what I claim as new, and desire to secure by Letters Patent of the United States, is—

1. In a quartz-mill, the combination with 60 the pan of mullers, consisting of sections of a flat ring, provided with inner and end flanges, the latter having opposite notches, of double-headed bolts dropped into said notches, to

couple the mullers loosely together, substantially as described.

2. In a quartz-mill, the combination with 65 the pan of mullers, consisting of sections of a flat ring, provided with inner and end flanges, the latter having opposite notches, of double-headed bolts dropped into said notches, to 70 couple the mullers loosely together, a vertical shaft, a yoke carried thereby, knees secured to the arms of the yoke, a cap or driving-ring secured on said knees, and a coupling-pin passed downward through the cap and into 75 the eye in one of the muller-coupling bolts, substantially as described.

3. In a quartz-mill, the combination with 80 a fixed horizontal pan and a set of revolving mullers, of an oppositely-driven cylinder and cylindrical shoes or rollers loosely set on end between the mullers and cylinder, substantially as described.

4. In a quartz-mill, the combination with 85 a fixed horizontal pan and a set of revolving mullers, of a central vertical cylinder and cylindrical shoes or rollers set loosely on end between the cylinder and mullers, substantially as described.

5. In a quartz-mill, the combination with 90 a fixed horizontal pan and a set of revolving mullers, of a central vertical cylinder, cylindrical shoes or rollers set loosely on end between the cylinder and mullers, and a circular screen surrounding the pan and projecting 95 above its edges, substantially as described.

6. In a quartz-mill, the combination with 100 a rigid, horizontal pan, of a vertical shaft projecting centrally through it and driven in one direction, a set of mullers connected with the shaft and rotating therewith, a bevel gear-wheel mounted loosely on the shaft and oppositely driven, a central cylinder in the pan connected with the gear-wheel and rotating therewith, and loose rollers or shoes 105 set on end in the pan between the mullers and cylinder, substantially as described.

7. In a quartz-mill, the combination with 110 a rigid horizontal pan, of a vertical shaft projecting centrally through it and driven in one direction, a set of mullers connected with the shaft and rotating therewith, a bevel gear-wheel mounted loosely on the shaft and oppositely driven a cylinder around the shaft and secured to the gear-wheel, a ring-clutch 115 on the cylinder having radial wings, a central cylinder in the pan having notches in its upper edge to receive the wings, and loose shoes or rollers set on end between the central cylinder and the mullers, substantially 120 as described.

A. T. MCMURTRY.
